UNITED STATES PATENT OFFICE.

SAMUEL FRANK, OF ST. LOUIS, MISSOURI, ASSIGNOR TO M. A. HEIMANN MANUFACTURING COMPANY, OF ST. LOUIS, MISSOURI, A CORPORATION OF MISSOURI.

SKIRT GAUGE.

Application filed December 22, 1921. Serial No. 524,185.

To all whom it may concern:

Be it known that I, SAMUEL FRANK, a citizen of the United States, residing at St. Louis, in the county of St. Louis City and State of Missouri, have invented new and useful Improvements in Skirt Gauges, of which the following is a specification.

This invention relates to a device for gaging the length of skirts, coats and other similar garments, and for assisting a dress maker or tailor in placing a circumferential mark upon the garment at a predetermined distance from the floor.

An object of the invention is to provide a device of this class which will facilitate the marking operation and enable the tailor to mark the garment accurately and quickly.

Another object of the invention is to produce a device which is of pleasing appearance, which may be cheaply manufactured, and which, by reason of the simplicity of its structure, is readily operable and durable in use.

Other objects of the invention have to do with the more detailed features of construction and will become more obvious as the description proceeds in connection with the accompanying drawings, wherein there is shown one form of a device in which the invention may be embodied, and in which—

Fig. 1 is a perspective view.

Fig. 2 is a sectional elevation showing the device in use, and

Fig. 3 is a horizontal cross section taken on the line 3—3 of Fig. 2.

Referring to the drawings for a more detailed description, 10 indicates a base to which there is secured a block 11 by any suitable means, such as a screw 12 passing through the base into the under face of the block. A standard 13 has its lower end fitting into the block and an arm 14 is pivotally secured to the block by means of a block 15 through which passes a pivot pin 16 anchored in the block 11 and about which the block 15 has a pivotal movement. The block 15 on the pivotal arm fits within a recess in the block 11 and the arm is normally maintained in the position shown in Fig. 2 by means of a spring 17 positioned beneath the block 15 and extending into a socket in the block.

A cross arm 18 is adjustably secured to the arm 14 by means of a collar 19 which may be held in any selected position along the arm by simply adjusting a set screw 20.

Upon the standard 13 is positioned a complementary cross arm 21 slightly wider than the cross arm 18 and adapted to be adjusted along the standard by a collar 22 and set screw 23. The cross arms are longitudinally curved to conform to the curvature of a garment, and are adapted to clamp between them the garment fabric along the line the mark is to be placed upon the garment. By having the cross arm 21 considerably wider than the arm 18, the cross arm 21 affords a bearing surface for the marking chalk and the edge of the cross arm 18 serves as a guide for the chalk.

In order to provide for the separation of the arm and standard it is desirable to afford some suitable means which will quickly separate the cross arms and hold the cross arms apart so that a garment may be inserted between the cross arms. In the form of the invention illustrated I have shown a lever 24 pivotally secured to the standard 13 adjacent the block 11 and held in position by a collar 25 fixedly secured to the standard. The lever 24 is formed with a laterally opening recess 26 having an inclined cam edge 27 leading to an annular seat at the inner end of the recess. When the lever 24 is moved in a counter-clockwise direction from the position shown in Fig. 3 the cam 27 engages the arm 14 and moves the arm from the standard, as shown in Fig. 1. Upon movement of the lever as far as possible in this direction the arm 14 will be brought into engagement with the seat at the termination of the recess and the cross arms will be held apart until the lever is returned to the position shown in Fig. 3. When a garment is inserted between the cross arms and it is desired to clamp the fabric for marking purposes it is merely necessary to move the lever 24 in a clockwise direction and the spring 17 will immediately move the parts to the clamping position shown in Fig. 2.

It is thought that the operation of this device will be clear from the above description of its structural features, particularly since these devices are broadly old in the art, my invention having to do with improvements upon the devices heretofore in use.

I wish to emphasize, particularly, the extreme simplicity of the structure and the facility with which the marking operation

- may be carried on when the device is used. The clamping cross arms may be made comparatively long so that the entire circumference of a dress or other garment may be
- 5 marked in two or three operations of clamping and unclamping the garment fabric. The length of the cross arms permits the marking of a considerable portion of the garment before turning the garment to present
- 10 another portion of the fabric to the cross arms. Moreover, the character of the means for separating the cross arms permits a very quick operation of the device with very little effort on the part of the operator.
- 15 It should be understood that numerous modifications may be made in the illustrated structure without departing from the inventive idea, the showing and detailed description being merely illustrative and in no sense
- 20 restrictive of the invention.

I claim:

1. A skirt gauge comprising a base, a standard connected to said base, an arm pivotally connected to the base, a cross-arm secured to said standard, a cross-arm secured to said pivoted arm, said cross-arms being adjustable along the standard and arm, spring means for holding the arm and standard together to clamp a skirt between the
- 25 cross-arms, and a cam pivoted to said standard and adapted to move and to hold the arm away from the standard thereby to permit the insertion of a skirt between the cross-
- 30 arms.

2. A skirt gauge comprising a base, an anchor block on said base having a recess therein, a standard having one end secured in said block, an arm having one end inserted in said recess and pivotally connected to said block, cross-arms on said standard and said arm, said cross-arms being adjustable along the standard and arm, spring means for holding together said standard and arm, and a lever pivoted to said standard having cam means thereon adapted to move and to hold the arm away from said standard.

3. A skirt gauge comprising a base, an anchor block on said base having a recess therein, a standard having one end secured in said block, an arm having one end inserted in said recess and pivotally connected to said block, cross-arms on said standard and said arm, said cross-arms being adjustable along the standard and arm, spring means for holding together said standard and arm, and a lever pivoted to said standard having cam means thereon adapted to move and to hold the arm away from said standard, one of said cross-arms being narrower than the other whereby the edge of the narrower cross-arm serves as a guide in marking and the wider cross-arm affords a bearing surface for the chalk.

In testimony whereof I have hereunto set my hand.

SAMUEL FRANK.
